AUTOMATIC FRUIT TUCKER

Hale Paxton, Redlands, Calif., assignor to Paxton Credit Corporation, Sanger, Calif., a corporation of California

Application May 24, 1932, Serial No. 613,224
Renewed May 7, 1935

18 Claims.

(Cl. 1—10)

My invention relates to box lidding machinery, and particularly to machines for nailing lids on boxes crown packed with fresh fruit and the like.

5 In the commercial packing of fresh fruits and the like for shipment to market, the product is placed in the box with what is known as a crown pack, the upper portion of the product in this pack forming a crown which extends above the upper edges of the box and the sides. In order to lid boxes thus packed it is necessary to press the lid down onto the box, with the final result that the lid is arched with the ends of the lid engaging the ends of the box to which the lid is 10 then nailed.

It has become the practice in the lidding of boxes packed in this manner to provide means for tucking the crown portion of the pack in between the lid and the box as the lid is being applied, 15 thus preventing serious damage to the product which would result if it were pinched between the box and the lid. This tucking apparatus is generally suspended with the lid nailing apparatus over the box to be lidded, and the suspended 20 mechanism is either lowered onto the box or the box is lifted into engagement with this mechanism so as to apply the lid to the box.

In tucking mechanisms hitherto employed, 25 which are automatically operated, the side flushers are mechanically operated in conjunction with the lidding operation so as to move inwardly and flush the crown fruit in at the sides of the box just at the right moment when the overhead mechanism is disposed at a given distance 30 from the upper edges of the box. Side flushers operating in this manner, however, have not heretofore been adaptable to flushing in the overflow in boxes of different heights.

It is accordingly an object of my invention to 35 provide side flushing mechanism which operates automatically in connection with the lidding of a box, and which does not require adjustment in order to successfully operate upon boxes which vary in height.

40 The manner of accomplishing the foregoing objects as well as further objects and advantages will be made manifest in the following description taken in connection with the accompanying drawings, in which:

45 Fig. 1 is a diagrammatic front elevational view of a box lidding machine with which is incorporated a preferred embodiment of my invention.

50 Fig. 2 is a fragmentary enlarged cross-sectional view taken on the line 2—2 of Fig. 1, and illus-

trating an intermediate step in the operation of the flushing means of my invention.

Fig. 3 is a view similar to Fig. 2 illustrating a final operative position of the flushing means of my invention.

Fig. 4 is an enlarged front elevational view of the flushing means shown in Fig. 1 showing the step in the operation thereof illustrated in Fig. 3.

Fig. 5 is a diagrammatic fragmentary perspective view illustrating the operating mechanism of 10 the side flushing means of my invention.

Referring specifically to the drawings, the preferred embodiment of the invention illustrated therein is incorporated with a lidding machine 10, this machine including a frame 11 having a 15 base 12, side standards 13, a transverse bar 14, and a transverse back stop 15.

Mounted on the frame 11 is an elevator 18 which includes a hydraulic cylinder 19 having a piston rod 20, upon the upper end of which is 20 mounted a box supporting platform 21, the latter being slidable vertically on the frame 11. The platform 21 has wheels 22 onto which a packed box 23 is adapted to be rolled from either side of the machine 10, automatic stops 24 being provided which hold this box 23 in the position in which it is shown in Fig. 1. The details of construction of the elevator 18 may be found in my copending application for U. S. Letters Patent Serial No. 577,388, filed January 18, 1932, for 30 box lidded.

Mounted on the frame 11 over the platform 21 so as to be in operative vertical alignment with the box 23 when it is properly positioned by the stops 24 on this platform is a lid supporting and 35 nailing mechanism 30, this mechanism having embodied with it means for tucking a crown portion of the fruit or the like packed in the box 23 inwardly as the lid is being applied to this box. To support the mechanism 30 the frame 11 has 40 forwardly extending brackets 35 which are connected by a pair of heavy cylindrical bars 36. Slidably mounted on the bars 36 so as to be adjustable laterally is a pair of plates 38, these being provided with spacers (not shown) which 45 unite these plates with the brackets 35 a desired distance from these brackets.

Mounted on inner faces of the plates 38 are nail chucks 40, each of which has a driver 41, these being connected to a vertically reciprocating driving head (not shown). Secured to the plates 38 are brackets 42, the inner ends of which support a crown sheet 43 and to the lower faces of which are secured lid flusher bars 45.

Extending downwardly from each of the flusher 50

bars 45 is a pair of legs 47, on the lower ends of which is pivotally mounted an end tucker 48, as shown in Fig. 5. Each of the tuckers 48 includes an inner spacer 50, outer spacers 51, and end 5 arms 52, a rod 53 extending through the spacers 50 and 51, the arms 52, and lower ends of the legs 47 to pivotally unite these elements. Pivotally mounted between the inner ends of the arms 52 is a tucker roller 55, and inner portions 56 of the 10 spacers 51 are formed to extend outwardly over the roller 55, as shown in Fig. 5. At opposite ends of the mechanism 30 yieldable lid centering arms 60 are spring mounted so as to be urged inwardly into the position in which these are illustrated in 15 Fig. 5.

Swingably mounted on the bars 36 is a pair of side flushers 70, each of which includes a frame 71 having hubs 72 from which side rods 73 extend downwardly, these rods having collars 74 20 on their lower ends. Slidable on the rods 73 are side flusher plates 75 which are connected by contractile springs 76 to the collars 74, as clearly shown in Fig. 4. Extending inwardly from the hubs 72 are apertured arms 78, the purpose of 25 which will be made evident hereinafter. Formed on the side flusher plates 75 and extending upwardly therefrom are lid guides 79. The side flushers 70 are positioned longitudinally on the bars 36 by collars 82 which are rigidly fixed to 30 the bars 36 and have arms 83 extending upwardly therefrom. Rockably mounted on the upwardly extending arms 83 are levers 85, the outer ends of which are pivotally connected to links 86, the lower ends of these links being pivotally connected to outward extensions of the arms 52. The 35 inner ends of the levers 85 are pivotally connected to rods 88 which extend downwardly through the apertures in the arms 78 and have nuts on their lower ends which confine contractile springs 89, so that these springs press upward against the 40 arms 78 of the flusher hubs 72. Provided on the rods 88 are collars 92 which are not only adapted to bear downwardly against the arms 78, but tend to swing the flushers 70 into their outward positions in which they are shown in Fig. 2. This 45 action results from the pressure of contractile springs 93 which are connected at their opposite ends to the rearmost pair of levers 85 and to the transverse bar 14, as shown in Figs. 2, 3, and 4.

50 When the term "presser head" is used in the claims it is to be understood as broadly indicating that overhead structure of the machine which operates with the box supporting table in pressing the lid onto a box resting on the table. In 55 the illustrated embodiment the presser head might be said to consist of the brackets 35, bars 36, plates 38, brackets 42, and possibly the crown sheet 43.

Operation

60 The operation of my invention is as follows: The tuckers 48 and flushers 70 and their connecting mechanism are positioned as shown in Fig. 1 during the intervals between lidding operations. 65 When a packed box, such as the box 23, is to be lidded it is run onto the supporting platform 21 from a suitable conveyor (not shown), and is stopped by the stops 24 in the position in which it is shown in this figure. When the box 23 is thus 70 positioned the end pieces 96 of the box are disposed directly beneath the end tucker rollers 55. The back stop 15 positions the box laterally so that sides 97 of the box 23 are disposed inwardly equal distances from beneath the side flusher plate 75, as clearly shown in Fig. 2.

For purposes of illustration, the box 23 is shown packed with fruit, such as apples, these extending above the box to form a crown 98, this crown being higher at the center than at the end, as shown in Fig. 1.

With the box 23 thus positioned on the platform 21, the elevator 18 is actuated to lift the box, thus bringing the box ends 96 into contact with the end tucker rollers 55. This causes these rollers to swing inwardly around the end tucker 10 shaft 53 and draws the rods 86 downwardly, thus rocking the levers 85, lifting the plungers 88, and swinging the side flushers 70 inwardly. This movement of the side flushers inwardly takes place just as the box sides 97 slide into position to 15 be contacted by the collars 74 of the flushers 70. This contact of collars 74 with the box sides prevents further inward movement of the flushers but permits the flusher plates 75 to engage the side rows of fruit in the crown 98 and press these 20 inward over the upper edges of the box sides 97. As the box 23 continues to rise the upper edges of the sides 97 engage the flusher plates 75 and lift these plates upwardly against the tension of the spring 76 until the box arrives at its uppermost 25 lid applying position in which the lid 100 is pressed onto the box 23 so that the lid conforms to the crown sheet 43 and the ends of the lid rest against the ends 96 of the box 23 just beneath the nail chucks 40. The position of the box at this 30 time is shown in Figs. 3 and 4. The nailing mechanism, not shown, is now actuated so as to move the nail drivers 41 downwardly and upwardly, thus nailing the ends of the lid onto the ends of the box. The elevator 18 may now be lowered 35 either under manual control or automatically, and the box 23, now lidded, is discharged from the platform 21 onto a suitable conveyor, not shown, provided to receive it.

It is now to be noted that the swinging inward 40 of the side flushers 70, accomplished as it is by the movement of the end tuckers responsive to their engagement with the ends of the box, takes place when the sides of the box have moved upwardly into a given relation with the side 45 flushers regardless of the height of the box being lidded. This is a great advantage where boxes of varying heights are packed and forwarded to the lidded 10 without these boxes being segregated. This is a common condition in 50 the apple packing industry where large numbers of half boxes are packed, as well as full boxes, from the same run of fruit.

The inward swinging of the end tuckers 48 results from the engagement of the end pieces 55 56 of the box with the tucker rollers 55 as the box moves upwardly. Owing to the fact the rollers 55 are normally disposed some distance below and inwardly from the axes on which the tuckers 48 are pivoted, the lifting of the rollers 55 60 swings these inwardly against any portion of the crown pack 98 extending over the box ends 96 so as to tuck this crown inwardly from over these box ends. It is furthermore noted that this operation takes place as the cover 100 is being 65 pressed onto the box 23. As the box moves on upwardly to completely press this cover with its ends on the ends of the box, as shown in Fig. 4, the end tucker rollers 55 swing outwardly as shown in this view against the outer faces of 70 the box ends 96. As the box descends after the nailing of its cover to the box the springs 93 return the tucking mechanisms to their normal position. In using the term "flusher" hereinabove and in the claims to define the side over- 75

flow gathering members of my invention it is to be understood that this term is to be broadly construed as covering any member which shifts overflow inwardly from over the side of the box.

5 While I have shown and described herein only a single preferred embodiment of my invention, it is to be understood that many changes and modifications might be made in this without departing from the spirit of the invention or the 10 scope of the appended claims.

What I claim is:

1. In a lidding machine the combination of: means for supporting a crown packed box; means for pressing a lid onto said box; means for tucking 15 end portions of said crown inwardly between said box and said lid during said pressing operation; means for flushing side portions of said crown between said box and said lid during said pressing operation; and means for operating said 20 side flushing means from said end tucking means.

2. A combination as in claim 1 in which said end tucker means is actuated by contact with upper edges of said box ends and relative vertical 25 movement between said box supporting means and said end tucking means.

3. A combination as in claim 1 in which said end tucker means is actuated by contact with upper edges of said box ends and relative vertical 30 movement between said box supporting means and said end tucking means and in which said side flushing means operates by swinging inwardly and yieldably resting on upper edges of the sides of said box.

35 4. In a lidding machine the combination of: supporting means for a crown packed box; end tucker supporting means; end tuckers pivoted on said end tucker supporting means on axes separated a greater distance than the length of 40 said box, said end tuckers extending downwardly and inwardly from said axes; means for moving one of said supporting means toward the other to cause said end tuckers to contact upper edges of ends of said box, thus swinging said end 45 tuckers inwardly; side flushers mounted alongside said box; and means connecting said end tuckers with said side flushers to cause actuation of said end tuckers to actuate said side flushers.

50 5. In a lidding machine the combination of: supporting means for a crown packed box; end tucker supporting means; end tuckers pivoted on said end tucker supporting means on axes separated a greater distance than the length of 55 said box, said end tuckers extending downwardly and inwardly from said axes; means for moving one of said supporting means toward the other to cause said end tuckers to contact upper edges of ends of said box, thus swinging said 60 end tuckers inwardly; side flushers mounted alongside said box; and means connecting said end tuckers with said side flushers whereby the swinging inward of said end tuckers yieldably swings said side flushers inwardly.

65 6. A combination as in claim 1 in which said side flushing means includes flushers mounted to swing inwardly over the sides of said box, means engaging the outer faces of said sides to stop said swinging, and yieldable means permitting said side flushers to assume the motion of said box upon said flushers contacting upper edges of said sides.

70 7. A combination as in claim 1 in which means is provided for returning said end and side flush-

ers to their normal positions upon the completion of a lidding operation.

8. A combination as in claim 1 in which both said end tucking and side flushing means are suspended from the frame of said lidding machine above a box as it is positioned on said box supporting means.

9. A combination as in claim 1 in which both said end tucking and side flushing means are suspended from the frame of said lidding machine above a box as it is received on said box supporting means, said tucking means and side flushing means also both being pivotally mounted horizontally and adapted to swing inwardly to accomplish their tucking and flushing functions.

10 10. A combination as in claim 1 in which the pressing of said lid on said box and the actuation of said end tucker is accomplished by the elevating of said box supporting means.

11. In a lidding machine the combination of: 20 means for supporting a crown packed box; means for pressing a lid onto said box to bring ends of said lid against ends of said box with said lid arched upwardly; side flushing means adapted to move inwardly to press a side portion of 25 said crown inwardly from over the sides of said box and maintain said flushing relation as said lid is pressed onto said box as aforesaid; and means for operating said flushing means to accomplish said flushing operation, said operating 30 means automatically adapting said flushing operation to boxes varying substantially in height.

12. A combination as in claim 11 in which said side flushing means is mounted above said box supporting means to yield vertically on a lid 35 supporting means; and means for moving one of said supporting means towards the other to press said lid on said box, said flushing means being operated to contact an upper edge of a side of said box and yield relatively to said lid supporting means during the pressing of the lid onto the 40 box.

13. In a lidding machine the combination of: a support for a crown packed box; an overhead structure; means on said structure for pressing 45 a lid onto said box; side flushers on said structure; means causing relative vertical movement between said support and said structure to press a lid onto said box by springing the lid ends down to the box ends while the middle of the lid bulges 50 upwardly to accommodate the crown of the pack; and means responsive to the top of the box approaching within a given distance of said structure to move said side flushers inwardly to press the overflow product inward from over the sides 55 of said box, the flushers thus being caused automatically to function uniformly on boxes varying in height.

14. In a lidding machine the combination of: a support for a crown packed box; means for 60 pressing a lid onto said box; side flushers having relative vertical movement towards said box during said lid pressing operation; and means responsive to the top of the box approaching within a given distance of said side flushers to 65 move said side flushers inwardly to gather the overflow product inward from over the sides of said box, the flushers thus being caused automatically to function uniformly on boxes varying in height.

15. In combination: a box supporting table; a presser head; means accomplishing relative vertical movement between said table and said presser head to press a lid onto a box on said table; a side flusher mounted on said presser 70 75

- head; means shifting said flusher inwardly into a given flushing position over a side of said box in timed relation with said relative movement, to press overflow product inward from over said side; and means permitting relative vertical movement between said presser head and said flusher to allow said flusher to remain in a position over said side after said flusher has been shifted into flushing position as aforesaid and during the consummation of said lid pressing operation.
16. In combination: a box supporting table; a presser head; means accomplishing relative vertical movement between said table and said presser head to press a lid onto a box on said table; side flusher support means mounted on said presser head for movement inwardly and outwardly relative thereto; a side flusher mounted on said support means for sliding movement up and down thereon; means shifting said flusher support means inwardly in timed relation with said relative movement to cause said flusher to move into a flushing position over a side of said box when separated vertically from said side a relatively short distance, said side flusher thereupon engaging said side and having sliding movement relative to said flusher support means during a continuation of the aforesaid relative vertical movement in the consummation of said lid pressing operation.
17. In combination: a box supporting table; a presser head; means accomplishing relative vertical movement between said table and said presser head to press a lid onto a box on said table; side flusher support means pivotally mounted on said presser head; a side flusher mounted on said support means for vertical sliding movement relative thereto; and means for swinging said flusher support means inwardly in timed relation with said relative movement to bring said flusher into flushing position over a side of said box just before said relative vertical movement results in contact between said side and said flusher, said contact causing said flusher to slide vertically upon said flusher support means during the consummation of said lid pressing operation.
18. In combination: a box supporting table; a presser head; means for elevating said table towards said head to press a lid onto a box on said table; side flusher support means pivotally mounted on said presser head; a side flusher mounted on said support means for vertical sliding movement relative thereto; and means for swinging said flusher support means inwardly in timed relation with the upward movement of said table to bring said flusher into a flushing position just above a side of said box, said side then rising into contact with said flusher causing the latter to slide upwardly relative to said support means and remain in flushing position relative to said box, as when contacted, during the consummation of said lid pressing operation.

HALE PAXTON.
